UNITED STATES PATENT OFFICE

148,201

DESIGN FOR A MOCCASIN

Louis Underberger, Farmington, N. H.

Application May 22, 1947, Serial No. 139,209

Term of patent 14 years

(Cl. D7—7)

To all whom it may concern:

Be it known that I, Louis Underberger, a citizen of the United States, residing at Farmington, county of Strafford, State of New Hampshire, have invented a new, original, and ornamental Design for a Moccasin, of which the following is a specification, reference being had to the accompanying drawings, forming a part thereof.

In the drawings:

Fig. 1 is a rear perspective view of a moccasin showing my new design; and

Fig. 2 is a rear elevation of the heel portion of the shoe.

I claim:

The ornamental design for a moccasin, as shown.

LOUIS UNDERBERGER.
